F. M. STOLL,
COLLAPSIBLE LUGGAGE CARRIER,
FILED AUG. 1, 1921.

UNITED STATES PATENT OFFICE.

FRANK M. STOLL, OF DENVER, COLORADO.

COLLAPSIBLE LUGGAGE CARRIER.

Application filed August 1, 1921. Serial No. 488,883.

To all whom it may concern:

Be it known that I, FRANK M. STOLL, a citizen of the United States, and a resident of the city of Denver, county of Denver, 5 State of Colorado, have invented certain and new useful Improvements in Collapsible Luggage Carriers, of which the following is a clear, full, and exact description, such as will enable others skilled in the art 10 to which it appertains to make and use the same, reference being had to the accompanying drawing, and to the figures of reference thereon, which forms a part of this specification.

15 My invention relates to improvements in collapsible luggage carriers of the type adapted to be clamped to the running board of an automobile, and has for its principal object the provision of luggage carrier of 20 this type, which will extend but slightly below said running board so that there will be no tendency for it to strike obstructions protruding from the road.

Another object is to provide a luggage 25 carrier that may fold parallel to and alongside of the running board of an automobile when not in use so that it will be entirely out of the way.

Still another object is to so construct the 30 luggage carrier that it may be raised to any height desired under its maximum height and will rigidly retain itself at this height.

A further object of the invention resides in the details of construction whereby the 35 carrier is rigidly braced against movement in any direction.

With these and other objects in view the 40 invention will now be described in detail, with reference to the accompanying drawing.

In this drawing,

Figure 1 is a side elevation of the invention attached to the running board of an automobile.

45 Figure 2 is a side elevation of the same showing the carrier only partially open.

Figure 3 is an enlarged cross sectional view taken on the line 3—3, Figure 1.

Figure 4 is a partial plan view taken at 50 the end of the carrier showing how the end gates are pivoted to the carrier proper.

Figure 5 is an enlarged end view of the luggage carrier in its collapsed or folded position.

Figure 6 is a cross sectional view taken 55 on the line 6—6, Figure 3, with the running board removed.

Corresponding and like parts are referred to in the following specifications and indicated in all views of the accompanying 60 drawings by the same reference characters.

Let the numeral 8 designate the luggage carrier in its entirety, consisting of a plurality of longitudinal bars 9, channel shaped in cross section. The bars 9 are held in 65 spaced relation to each other by means of two sets of lazy tongs 10 and 11. The longitudinal bars are pivoted to lazy tongs 10 and 11 at the points of intersection of the bars thereof.

70 Two of the bars in each set of lazy tongs are relatively longer than the other bars therein, and intersect at point outside of the lazy tongs proper. These points of intersection are designated by the numerals 12 75 and 13. As the points of intersection 12 and 13 have a horizontal motion in addition to their pivotal motion, as the carrier 8 is raised and lowered, the pivot pins thereof are slidably mounted in slots 14 and 15, respectively formed in one of the horizontal bars 9.

75 The object of these longer bars and their bearing slots is to rigidly brace the carrier 8 against horizontal movement while allowing it freedom to move vertically.

The lowermost point of intersection of each lazy tongs 10 and 11 is pivoted to clamps 16 as shown at 17 adapted to be clamped to the running board of an auto- 90 mobile.

95 Clamps 16 are composed of a hollow frame 18 which extends upward and forward forming the upper jaw of the clamp, and downward and outward to support the pivotal points 17 of the lazy tongs.

The lower jaw 19 of clamp 16 consists of a solid L shaped bar, the horizontal leg forming the jaw proper, the vertical leg being slidably mounted in the hollow, vertical portion of the frame 18. Through the center of the vertical leg and parallel with its length a threaded hole 20 is formed. A bolt 21 passes downward through the top of frame 18 and engages in the threaded hole 105 in the upright leg of lower jaw 19. It will be readily seen that upon turning the bolt 21 the lower jaw 19 of the clamp 16 can be

made to travel vertically for clamping or unclamping from the automobile running board.

The applicant has found that all bolt heads or nuts of any kind projecting below the clamp are very objectionable, by reason of the fact that they catch and drag upon the road and obstructions thereon when the wheels of the automobile are in deep ruts. 10 It was to overcome this objection that the bolt head was placed above the running board.

Pivoted to each of the clamps 16 are vertical braces 22. Braces 22 are L shaped in 15 cross section, the two legs of the L being folded together at their upper extremities as shown at 23 and are pierced by bolts 24 upon which are threaded wing nuts 25.

The two edges of the channel shaped 20 upper bar 9 are turned inward forming a slot along which the bolts 24 travel, held therein by means of the bolt heads 26. This slot extends the length of the bar between the lazy tongs supports as indicated in 25 broken lines in Figure 2.

The lower extremities of braces 22 are broadened out at the axis of the pivot as 30 shown at 27, Figure 3. This forms a wide base for the braces, and causes them to rigidly resist any side pressure put on the carrier 8.

Each end of the carrier is provided with an end gate 28 consisting of horizontal bars 35 29 which are pivoted to the extremities of horizontal bars 9. The bars 29 are channel shaped in cross section and are adapted to nest within the bars 9 when the carrier is collapsed, as shown in Figure 5.

Toggle arms 30 are placed between the 40 extremities of the horizontal bars 29 to prevent luggage from falling between said bars.

The luggage carrier may be collapsed from the position shown in Figure 1 to that of Figure 5 in the following manner:—The 45 horizontal bars 29 of both end gates 28 are folded within horizontal bars 9. Thumb nuts 25 at the upper extremities of both braces 22 are loosened. Said extremities are then drawn towards each other, as indicated in Figure 2, the bolts 24 traveling along the slot in the top longitudinal bar 9. By tightening the nuts 25 any desired height will be maintained. As the upper extremities of the braces 22 approach each other, the 55 lazy tongs close and bring the horizontal bars 9 together.

In the fully collapsed position the horizontal bars are together and resting on the outward projecting portion of clamp case 60 18. The projecting extremities 12 and 13 of the lazy tongs are now at the inner terminals of the slots 14 and 15, the bars of the lazy tongs are folded against each other; and the braces 22 lie along the top of the 65 running board parallel with the top hori-

zontal bar 9. The thumb nuts 25 may now be tightened and the whole device rigidly locked in the collapsed position, so that there will be no rattle from the vibration of the automobile.

If desired the bolts 21 may now be loosened, thus releasing the lower jaws 19 of the clamps 16 from the running board and the complete carrier removed from the automobile.

Having thus described my invention, what I claim and desire to secure by Letters Patent is:—

1. A luggage carrier for automobiles comprising a series of horizontal bars adapted to move vertically and held in spaced relation by lazy tongs; means for causing said lazy tongs to resist endwise movement of said horizontal bars; clamps adapted to grip the running board of an automobile and pivotally connected with the lower extremities of said lazy tongs; braces pivoted to said clamp and adapted to hold said lazy tongs in an extended position and to resist sidewise movement of said horizontal bars. 90

2. A luggage carrier for automobiles comprising a series of horizontal bars adapted to move vertically and held in spaced relation by lazy tongs; means for causing said lazy tongs to resist endwise movement of said horizontal bars; clamps adapted to grip the running board of an automobile and pivotally connected with the lower extremities of said lazy tongs; braces pivoted to said clamp and adapted to hold said lazy tongs in an extended position and to resist sidewise movement of said horizontal bars; end gates pivotally connected to each extremity of said horizontal bars and adapted to fold therein. 100

3. A luggage carrier for automobiles comprising horizontal bars held in spaced relation by lazy tongs, said lazy tongs adapted to brace said horizontal bars against endwise movement; a clamp adapted to grip the running board of an automobile pivotally connected to said lazy tongs, said clamp comprising a lower and upper jaw; means for operating said jaws from a point above said running board. 110

4. A luggage carrier for automobiles comprising a series of horizontal bars held in spaced relation by means of lazy tongs; means for bracing said horizontal bars against endwise and sidewise movement; clamps pivoted to the lower extremities of said lazy tongs and adapted to grip the running board of an automobile, said clamps comprising a fixed upper jaw and frame with a movable lower jaw slidably mounted therein, said lower jaw being actuated by means of a bolt threaded therein and extending out through said upper jaw. 120

5. A luggage carrier for automobile running boards comprising a series of horizontal 130

bars held in spaced relation by means of vertical lazy tongs; means for bracing said horizontal bars against endwise movement consisting of running two bars of said lazy tongs to a point of intersection exteriorly of said tongs, said point of intersection being slidably mounted upon one of said horizontal bars; means attached to said lazy tongs for connecting said carrier to an automobile running board.

6. A luggage carrier for automobiles comprising horizontal bars held in spaced relation by vertical pairs of lazy tongs; means

for maintaining said lazy tongs vertical; clamps pivotally attached to said lazy tongs and adapted to attach to the running board of an automobile; means for maintaining said lazy tongs in their extended position, said means consisting of braces pivoted at their lower extremities to said clamps, having their upper extremities slidably mounted in the upper bar of said horizontal bars; means for locking said upper extremities at any desired point on said upper bar.

In testimony whereof I affix my signature.

FRANK M. STOLL.
